DESIGN FOR A COMBINED HAT AND TIE RACK

Arnold B. Mallins, West Hempstead, N. Y.

Application July 15, 1944, Serial No. 114,410

Term of patent 7 years

(Cl. D33—8)

To all whom it may concern:

Be it known that I, Arnold B. Mallins, a citizen of the United States, residing in West Hempstead, Nassau County, of New York, have invented a new, original, and ornamental Design for a Combined Hat and Tie Rack, of which the following is a specification, reference being had to the accompanying drawing, forming part thereof.

In the drawing:

bined hat and tie rack showing my new design; and

Figure 2 is a sectional view taken along the line and looking in the direction of the arrows 2—2 of Figure 1.

I claim:

The ornamental design for a combined hat and tie rack, as shown.

ARNOLD B. MALLINS.
